UNITED STATES PATENT OFFICE.

GLENN BOGDONOFF, OF NEW YORK, N. Y., ASSIGNOR OF ONE-HALF TO R. K. M. MFG. CO., OF NEWARK, NEW JERSEY, A CORPORATION OF NEW JERSEY, AND ONE-HALF TO ALBERTS MFG. CO., INC., OF HACKENSACK, NEW JERSEY, A CORPORATION OF NEW JERSEY.

TAPE REVERSING AND FEEDING ATTACHMENT FOR SEWING MACHINES.

Application filed September 20, 1922. Serial No. 589,309.

This invention relates, generally, to improvements in sewing machines employed in the art of attaching tapes provided with the usual garment-fasteners, such as hooks or eyes, to garments; and the present invention has reference, more particularly, to a novel and simply constructed, as well as an efficiently operating guiding means for sewing machines, for feeding such attaching strips or tapes, with the garment-fasteners, properly beneath the needles of the sewing machine, for sewing the strips or tapes to the garments, and without danger of crushing the said garment fasteners.

The invention has for its principal object to provide a novel and simply constructed guiding means for sewing machines, for the purposes herein-above stated, with a view of rapidly and properly presenting the strips or tapes, with the garment-fasteners attached thereto, upon the sewing table of the machine, and beneath the sewing needles thereof, for the attachment of such strips or tapes to the garments, with the garment-fasteners, such as the hooks and eyes, properly spaced with relation to the upper and lower edges of the garment, to which the strips or tapes are being attached.

Other objects of the present invention not at this time more particularly enumerated will be clearly understood from the following detailed description of the present invention.

With the various objects in view, the present invention consists, primarily, in the novel guiding means for sewing-machines hereinafter more fully set forth; and the said invention consists, furthermore, in the novel arrangements and combinations of the various devices and parts, as well as in the details of the construction of the said parts, all of which will be more fully described in the following specification, and then finally embodied in the clauses of the claims, which are appended to and which form an essential part of the said specification.

The invention is illustrated in the accompanying drawings, in which:

Figure 1 is a top or plan view of a guiding means for sewing machines, showing one em-

bodiment of the principles of the present invention, said view representing in connection therewith a fragmentary portion of the sewing machine table to which said feed-attachment is attached.

Figure 2 is a side elevation of the said guiding means, looking in the direction of the arrow *x* in said Figure 1.

Figure 3 is a perspective view of a setting gauge used with the guiding means, said view showing in connection therewith a fragmentary portion of the base-plate forming a part of the guiding means, and a fragmentary portion of the fastener-provided tape, as it passes along the side of said setting gauge, and prior to passing beneath the needles to be sewed fast to the garment; and Figure 4 is a perspective view of one of a pair of adjusting guides employed with the guiding means attachment.

Figure 5 is a transverse vertical sectional representation, said section being taken on line 5-5 in said Figure 1, looking in the direction of the arrow *y*.

Figure 6 is a perspective view of a combined feed-plate and tape-feeding guide forming a part of the guiding means, said view showing in connection therewith the relative positions of the sewing needle, raised above the feed-plate.

Figure 7 is a transverse vertical sectional representation of the guiding means, said section being taken on line 7-7 in said Figure 1, said view showing in connection therewith a cross-sectional representation of the tape provided with garment fasteners in the form of hooks, one of which is presented in elevation; and Figure 8 is a similar cross-sectional representation of the guiding means, said view also showing in connection therewith a cross-sectional representation of a tape provided with garment fasteners in the form of eyes, one of which is represented in elevation, said Figures 7 and 8 being made on enlarged scales.

Figure 9 is a transverse vertical sectional representation and part perspective of a portion of the guiding means, said section being taken on line 9-9 in Figure 1.

Figure 10 is a perspective view, showing

diagrammatically the movement of the tape as it passes through the guiding means, said view illustrating in connection therewith the relative positions of the setting 5 gauge and of the adjusting guides.

Figures 11 and 12 are views of the respective opposite faces of a portion of the tape provided with garment fasteners in the form of hooks; Figures 13 and 14 are views 10 of the respective opposite faces of a portion of the tape provided with garment fasteners in the form of eyes; and Figure 15 is a view, partly in cross-section and partly in perspective, of fragmentary portions of a 15 piece of tape provided with garment fasteners, in the form of hooks, and a garment, showing the tape and garment fasteners sewed fast to the garment.

Similar characters of reference are employed 20 in all of the said above described views, to indicate corresponding parts.

Referring now to the several figures of the drawings, the reference character 1 indicates the sewing table of any usual sewing machine provided with the usual foot-bar 2 which carries the presser-foot 3, substantially as shown in Figure 2 of the drawings. Connected with the usual head 4, which carries the said foot-bar 2, are the needle-bars 5, two of such last-mentioned bars being employed in the present instance, and each needle-bar 5 having secured thereto, in any suitable manner, a sewing needle 6 of any usual construction, for sewing portions of 30 the tapes 7 or 8, respectively provided with spaced hooks 9 and eyes 10 to a garment, as will be understood.

In practice, these tapes 7 or 8, with the garment fasteners suitably spaced and secured thereto, are furnished in large rolls 40 by one manufacturer to the garment worker or manufacturer, such fastener-provided tapes being wound upon reels which are suitably placed beneath or upon the bench carrying the sewing machine, to be fed by the guiding means, embodying the principles of 45 the present invention, directly upon the sewing table 1, to pass over the channeled feed-plate 32 and beneath the presser-foot 3 and 50 the needles 6 for stitching the tape to the garment.

As shown in the several figures of the drawings, the hooks 9 and the eyes 10 are suitably spaced in series of five fasteners 55 upon the respective strips or tapes 7 and 8, providing between the series of fasteners a space, as 11, known as the cut-off, as will be evident from an inspection more particularly of Figures 1, 11 and 13 of the drawings. It will be apparent, however, from 60 the following description of the drawings, that the garment fasteners may be different-ly spaced, and the number of fasteners in each series may be greater or less than five, 65 as here shown, and that the same guiding

means, owing to the adjustability of cer-tain of its parts, may still be used without removal from the sewing machine, with strips or tapes having different series of said garment fasteners.

It will be necessary to state at this time, that the tapes with their attached garment fasteners are reeled in such a manner, that in order to bring the fasteners, when passing beneath the sewing needles, in the relative 70 positions so as to extend downwardly from the tape, as shown in Figures 7, 8 and 15 of the drawings, the tape during the feeding operations has to be looped, as at 12, see Figures 2 and 10 of the drawings, and one of the principal objects of the present invention, therefore, is to provide a guiding means which will produce such looping of the strip or tape. In other words, the guiding means is constructed and operates in such a manner, that during the feeding operation, the garment fasteners will first be presented upwardly, so that they can be seen by the operator, but will be presented downwardly while the tape is being sewed fast to the garment, 75 so that the fasteners are not seen by the operator, the device working properly, so that the sewing operations are rapidly performed, and with all danger of the operator making any mistake eliminated.

The guiding means herein above mentioned comprises a main member or element, in the form of a suitably shaped plate 13, adapted to be placed in position relative to the sewing table 1, by slipping its longitudinally extending marginal edge-portions 14 and 15 into properly placed receiving grooves or channels, as 16 and 17, see Figure 5 of the drawings, with which the said sewing table 1 is provided. It will be under- 105 stood, however, that the said plate 13 may be secured in any other suitable manner in its operative position upon the said sewing table 1 of the sewing machine, if desired. Suitably connected with the said plate 13 110 is a forwardly extending guide-member 19, the forward end-portion of which extends downwardly, as at 20, and is then curved rearwardly, as at 21, and then upwardly, as at 22, so as to provide a loop, as 23, substan-tially, as indicated in the several figures of 115 the drawings. As shown, the said guide-member 19, and its portions 20, 21 and 22, are provided along their marginal edge-portions with marginal ribs 24 and 25, so as to 120 provide a guideway of suitable width to receive the fastener-provided strip or tape, and properly guide the same upon the channeled feed plate 32 and beneath the presser-foot and the sewing needles of the machine in 125 the manner and for the purposes to be hereinafter more fully described. As will be seen from an inspection of Figure 2 of the drawings, one of the said marginal ribs, as 24, extends beyond the curved edge-portion 130

26 of the portion 22, so as to provide a suitably curved strengthening brace, as 27, being suitably secured in its fastened position by means of screws 28, or other suitable fastening means, as will be evident. A bracket, as 29, may also be provided for retaining the said parts 20, 21 and 22 in a rigid relation to each other, and to maintain a loop 23, of the desired and proper shape. It will be understood, however, that in lieu of the strengthening brace 27 and the bracket 29, other means may be employed for maintaining the proper relation of the various parts.

In addition, the said plate 13 may be provided with a downwardly projecting member, as 30, which serves as a fingerpiece for clipping the said plate into its operative position upon the sewing table 1 of the sewing machine, or for removing it therefrom, if desired. In alignment with the end-portion 31 of the guide-member 19 is a suitably formed feed plate, which as will be seen from an inspection of Figures 1, 2, 6, 7 and 8 of the drawings, consists of a main plate 32 usually provided with perforations 33 for the reception of screws by means of which the said plate is secured in its proper position upon the sewing table 1 of the sewing machine.

This plate 32 is also provided with suitably disposed openings, as 34, in which the feed dogs (not shown) common to sewing machines are adapted to reciprocate, the said plate 32 being also provided with suitably disposed ribs or upwardly projecting members, as 35, which serve as guides for the margins of the fastener tape and prevent lateral displacement of the fastener-provided strip or tape relative to the sewing needles, presser foot and cooperating feed-dogs. The said presser-foot is also made with openings, as 36, in alignment with the previously mentioned openings 34, so as not to interfere with the reciprocatory movement and sewing operations of the sewing needles 6. Suitably secured by means of screws 37, or otherwise, upon the upper surface of the plate 13 and at one side of the guide-member 19 is a plate 38 upon which is mounted by suitable fastening means, as 39, a hemmer 40 to turn the edge of the garment material to which the fastener-tape is to be sewn, said hemmer having the usual curved goods turning members or portions 43 and 44, all arranged so that the raw edge of the garment is turned or hemmed before meeting the fastener-tape passing beneath said hemmer, and thence passing with the fastener-tape beneath the presser foot and over the feed-plate subject to the sewing operations of the sewing needles. Secured by screws 41 is a member 42 which spans the tape guideway beneath the hemmer 40.

When the fastener-provided strip or tape 7 provided with the hooks 9 is used with the

guiding means, the previously described feed-plate is provided in its body 32 with a guide-channel 45 for the reception and movement therethrough of the projecting end-portions of the hooks 9, as shown in Figures 6 and 7 of the drawings, and if desired one side of said channel may be undercut as at 46 to engage the tip of the hook. The said guide-channel 45 lies beneath and intermediate the sides of the presser foot, and provides a clearance passage for the hooks of the fastener tape, so that descent of the presser foot will neither engage said hooks, so as to interfere with the forward movement of the tape, nor crush said hooks during the sewing operations. When a fastener-provided strip or tape 8 provided with eyes 10 is used with the feed-attachment, then such guide-channel 45 may, if desired, be omitted from the base 32 of the feed-plate, as will be fully understood from an inspection of Figure 8 of the drawings.

Also suitably secured upon the plate 13, at the side of the guide-member 19 opposite the plate 38 which is provided with the hemmer 40 is a setting gauge, illustrated more particularly in Figures 1 and 3 of the drawings, the said gauge comprising a main base-plate 47 upon which is movably disposed a slide 48. This slide is provided with an elongated opening or slot 49, and with a laterally projecting gauging finger 50 which extends over the tape and is arranged at such a height that it will not interfere with the movement of the tape therebeneath. Disposed above the said opening or slot 49 of the slide 48 is a fastening or securing plate 51, provided with screw-receiving perforations 52 for the reception of the screw-threaded shanks of thumb-screws 53, the shanks of which are passed into and through the previously mentioned opening or slot 49 and then screwed into the screw-threaded holes 54 correspondingly located in the base-plate 47. By slightly unscrewing the thumb-screws 53, the slide 48 and the gauging finger 50 may be moved in either direction, so as to be properly adjusted for the purposes hereinafter more fully described, and then secured in its adjusted position by screwing down the thumb-screws and causing a fixed and clamped relation between the fastening or securing plate 51, the slide 48, and the main base-plate 47, as will be clearly evident.

Another guide-member of the guiding means is indicated by the reference-character 55, this member being suitably secured at one end to the previously mentioned plate 13, and extending rearwardly from said plate, preferably, at an acute angle to the said guide-member 19 and its parts, substantially as shown in Figure 1 of the drawings. The said guide-member 55 is also provided along its marginal edge-portions with marginal ribs 56 and 57, so as to pro-

vide a guiding space of suitable width to receive the fastener-provided strip or tape, and guide the same over the previously mentioned loop 23 and upon the guide-member 19. At its receiving end, the said guide-member 55 has secured thereon by means of screws 58, or in any other suitable manner, a bridge-plate 59 having an upwardly curving part, as 60, for the proper insertion of the free end of the strip or tape, and the arrangement of the tape in the tape-receiving space of the guide-members, prior to the sewing operation of the sewing machine. At its discharge-end, the said guide-member 55 is provided with a downwardly curving extension, as 61, which terminates in close proximity directly above the upwardly curved part 22 of the loop 23, for properly moving the strip or tape from said guide-member 55 upon and over said loop 23 and upon the guide-member 19, as will be clearly understood from an inspection of Figures 1 and 2 of the drawings. As an extra precaution, the edge-portion of the plate 13, directly beneath this curved extension 61 is also correspondingly curved in a downward direction, as at 62, to provide a means for positively guiding the feeding operation of the fastener-provided strip or tape. In connection with the said guide-member 55, I prefer to use a pair of adjustably disposed space-indicating members or guides 63 and 64, each guide consisting of a main body-plate 65 adapted to be placed so as to bridge over the receiving space of the guide-member 55, and provided with curved or hook-shaped marginal embracing members, as 66 and 67, see Figure 4 of the drawings, which respectively embrace the marginal ribs 56 and 57 of the guide-member 55 in a loose manner, so that the said guides 63 and 64 may be slid back and forth upon the ribs of the guide-member 55 for the desired adjustment thereon, and for the purpose to be presently set forth. One means of immovably securing said guides 63 and 64 in their adjusted positions, is in the form of thumb-screws 68, the screw-threaded shanks of which are screwed into and through screw-threaded holes 69 with which the plates 65 are provided, so that the free ends of the shanks of the said screws 68 and the embracing members 66 and 67 of the respective guides 63 and 64 will be brought positively into frictional holding engagement with the said guide-member 55, so as to immovably fix the said guides 63 and 64 in their adjusted bridging relation to the said guide-member 55, as will be clearly understood.

Having in the foregoing description set forth a construction of strip or tape guiding means illustrating one embodiment of the principles of the present invention, I will now briefly set forth the manner of using

the same for properly feeding tape, whether provided with hooks or eyes, and no matter how said fasteners are spaced apart upon the tape, with the garment, to the edge of which the fastener-provided tape is to be attached, and so that the tape passes between the feed-plate and the presser-foot of the sewing machine, subject to the operation of the sewing needles at both of its longitudinal marginal edge portions.

Before starting the sewing machine, the operator prior to inserting the free end of the strip or tape between the inserting or receiving end of the guide-member 55 and the bridge-plate 59, by means of scissors or shears, first cuts off a portion of the tape, so as to bring the first garment fastener the proper distance from the end of the tape to correspond to the distance that said first fastener, when the tape is sewn fast to the garment, is to be located from the upper edge of the garment. The tape, with its face-portions from which the garment fasteners are upwardly exposed, is now passed upon the said guide member 55, with the fasteners thus exposed to the view of the operator, the same being led down upon and over the loop 23, and thence upon the guide-member 19, in consequence of which the tape becomes arranged in a reversed position upon said guide-member 19, with the garment fasteners thereupon located upon the underside of the tape, so that they are not seen by the operator. The operator then continues to move the tape upon the guide-member 19 in a direction toward the lowered sewing needles until the free end of the tape is brought against the needles, the tape passing between the ribs or projections of the feed plate 32, and if provided with fasteners of hook form, the hooks being disposed in the channel 45 of said feed plate. The gauging finger 50 of the slide 48 of the setting gauge is now moved into registering position with the exposed stitching or threads, as 70, see Figure 1, which secure the garment fasteners to the tape, of the first fastener of the second series of garment fasteners, and the gauging finger is then securely fixed in its adjusted position by means of the previously mentioned thumb-screws 53 and the fastening or securing plate 51. The operator next loosens the adjusting guides 63 and 64, adjusting them in such position upon the guide-member 55, that a series of the upwardly exposed garment fasteners upon the tape will be located between the said guides 63 and 64, as will be clearly evident from an inspection of Figures 1 and 10 of the drawings. After such adjustment of the guides 63 and 64 has been made the operator is ready for the sewing operation of the sewing machine with which the guiding means is used.

From an inspection of said Figure 1, it

will be evident, that the purpose of the said guides 63 and 64, after they have been fixed in the adjusted positions by tightening the thumb-screws connected with the same, is to 5 provide a means of indication, so as to enable the operator to readily observe that the same number of fasteners in each succeeding series of fasteners, will be presented; and, furthermore, to enable the operator to quickly observe, when there are any missing garment 10 fasteners in the series of fasteners, as the strip or tape passes along the guide-member 55 of the guiding means.

Prior to the operation of sewing the fastener-provided strip or tape to the garment, 15 that portion of the tape initially located between the gauging finger 50 and the lowered sewing machine needles, as has just been related, may be pulled back so that the first- 20 located fastener of the free end-portion of the tape is brought into gauging relation with the finger 50. The garment 71, to the edge of which the tape is to be sewed fast, is now passed through the hemmer 40 so as to 25 be properly placed over the leading end of the tape, with the upper marginal edge of the garment in registration with the free end-portion of the tape, and then jointly fed by the operator toward and beneath the reciprocating sewing machine needles, so that, 30 as the machine is set in motion, both longitudinal edges of the fastener-provided tape are properly sewn fast to the edge portion of the garment.

In this manner, garment after garment is 35 easily and quickly fed with the tape beneath the sewing needles, and the sewed-fast portions of the tape being severed or cut by the operator, with scissors or shears across the "cut-off" spaces of the fastener tape, as will 40 be understood.

Of course I am fully aware, that various changes may be made in the general arrangements and combinations of the various devices and parts, as well as in the details of the construction of the said parts, without departing from the scope of the present invention as set forth in the foregoing specification, and as defined in the clauses of the 45 50 55 claims which are appended thereto. Hence, I do not limit my invention to the exact arrangements and combinations of the various devices and parts as described in the said specification, nor do I confine myself to the exact details of the construction of the said parts, as illustrated in the accompanying drawings.

I claim:

1. A guiding means for sewing machines 60 for sewing fastener provided tape to garments, comprising a plurality of guide-members for receiving and guiding the tape to the sewing machine needles, and means interposed between the said guide-members 65 for reversing the tape as it passes from one

guide-member to the other guide-member, combined with a feed-plate, said plate being formed with a fastener-receiving channel.

2. A guiding means for sewing machines 70 for sewing fastener provided tape to garments, comprising a plurality of guide-members for receiving and guiding the tape to the sewing machine needles, and a loop-shaped element interposed between the said guide-members for reversing the tape as it 75 passes from one guide-member to another guide-member, combined with a feed-plate, said plate being formed with a fastener-receiving channel having an undercut portion.

3. A guiding means for sewing machines 80 for sewing fastener provided tape to garments, comprising a main base-plate, a pair of guide-members for receiving and guiding the tape to the sewing machine needles, means interposed between the said guide-members for reversing the tape as it passes from one guide-member to the other guide-member, adjusting guides movably disposed upon one of said guide-members, and a setting gauge upon said base-plate having a setting finger extending over the other guide-member.

4. A guiding means for sewing machines 85 for sewing fastener provided tape to garments, comprising a main base-plate, a pair of guide-members for receiving and guiding the tape to the sewing machine needles, means interposed between the said guide-members for reversing the tape as it passes from one guide-member to the other guide-member, adjusting guides movably disposed upon one of said guide-members, and a setting gauge upon said base-plate having a setting finger extending over the other 90 95 100 105 guide-member, combined with a feed-plate, said feed-plate being formed with a fastener-receiving channel.

5. A guiding means for sewing machines 110 for sewing fastener provided tape to garments, comprising a main base-plate, a pair of guide-members for receiving and guiding the tape to the sewing machine needles, a loop-shaped element interposed between the said guide-members for reversing the tape 115 as it passes from one guide-member to the other guide-member, adjusting guides movably disposed upon one of said guide-members, and a setting gauge upon said base-plate having a setting finger extending over the other 120 guide-member.

6. A guiding means for sewing machines 125 for sewing fastener provided tape to garments, comprising a main base-plate, a pair of guide-members for receiving and guiding the tape to the sewing machine needles, a loop-shaped element interposed between the said guide-members for reversing the tape as it passes from one guide-member to the other guide-member, adjusting guides mov-

ably disposed upon one of said guide-members, and a setting gauge upon said base-plate having a setting finger extending over the other guide-member, combined with a feed-plate, said feed-plate being formed with a fastener-receiving channel having an undercut portion.

7. A guiding means for sewing-machines for sewing fastener provided tape to garments, comprising a main base plate, a tape-receiving guide-member connected with said base-plate, said guide-member terminating in front of said base-plate with a downwardly extending and rearwardly projecting tape-reversing loop-member, and a second tape-receiving guide-member also connected with said base-plate and having a discharging end-portion terminating contiguous to and above the free end-portion of said loop-member.

8. A guiding means for sewing machines for sewing fastener provided tape to garments, comprising a main base plate, a tape-receiving guide-member connected with said base-plate, said guide-member terminating in front of said base-plate with a downwardly extending and rearwardly projecting tape-reversing loop-member, and a second tape-receiving guide-member also connected with said base-plate and having a discharging end-portion terminating contiguous to and above the free end-portion of said loop-member, combined with a feed-plate, said feed-plate being formed with a fastener-receiving channel.

9. A feed attachment for sewing-machines for sewing fastener provided tape to garments, comprising a main base plate, a tape-receiving guide-member connected with said base-plate, said guide-member terminating in front of said base-plate with a downwardly extending and rearwardly projecting tape-reversing loop-member, and a second tape-receiving guide-member also connected with said base-plate and having a discharging end-portion terminating contiguous to and above the free end-portion of said loop-member, adjusting guides movably disposed upon said second-mentioned guide-member, and a setting gauge upon said base-plate having a setting finger extending over said first-mentioned guide member.

10. A guiding means for sewing machines for sewing fastener provided tape to garments, comprising a main base plate, a tape-receiving guide-member connected with said base-plate, said guide-member terminating in front of said base-plate with a downwardly extending and rearwardly projecting tape-reversing loop-member, and a second tape-receiving guide-member also connected with said base-plate and having a discharging end-portion terminating contiguous to and above the free end-portion of said loop-member, adjusting guides movably disposed

upon said second-mentioned guide-member, and a setting gauge upon said base-plate having a setting finger extending over said first-mentioned guide-member, combined with a feed-plate, said feed-plate being formed with a fastener-receiving channel having an undercut portion.

11. A guiding means for sewing machines for sewing fastener provided tape to garments, comprising a main base plate, a tape-receiving guide-member connected with said base-plate, said guide-member terminating in front of said base-plate with a downwardly extending and rearwardly projecting tape-reversing loop-member, and a second tape-receiving guide-member also connected with said base-plate and having a discharging end-portion terminating contiguous to and above the free end-portion of said loop-member, combined with a garment edge 85 hemmer mounted upon said base-plate to overhang said first mentioned guide-member, and a feed-plate extending from the inner end of said first mentioned guide-member beneath the sewing needles of the machine. 90

12. A feed attachment for sewing-machines for sewing tape provided with garment fasteners to garments, comprising a main base plate, a tape-receiving guide-member connected with said base-plate, said guide-member terminating in front of said base-plate with a downwardly extending and rearwardly projecting tape-reversing loop-member, and a second tape-receiving guide-member also connected with said base-plate and having a discharging end-portion terminating contiguous to and above the free end-portion of said loop-member, combined with a garment edge hemmer mounted upon said base-plate to overhang said first mentioned guide-member, and a feed-plate extending from the inner end of said first mentioned guide-member beneath the sewing needles of the machine, said feed-plate being formed with a fastener-receiving channel. 105

13. In combination with a sewing-machine for sewing fastener-provided tape to a garment, means for guiding the tape with its fasteners extending upwardly from one of the faces of the tape toward the machine, means for reversing the tape and guiding the tape with its fasteners extending downwardly from said face of the tape, and a feed-plate toward and above which the tape is fed, said feed-plate being formed with a fastener-receiving channel. 115

14. In a two-needle sewing machine for sewing fastener provided tape along both longitudinal edges, a feed-plate over which the tape may move, a presser foot adapted to contact therewith, and said feed plate having a longitudinal channel intermediate the sides of and beneath the presser foot and so as to be straddled by the sewing needles, said channel being adapted to permit the un- 130

obstructed passage of fasteners of the tape beneath said presser foot.

15. In a two-needle sewing machine for sewing fastener-provided tape along both 5 longitudinal edges, a feed-plate over which the tape may move, a presser foot adapted to contact therewith, said feed plate having a longitudinal channel intermediate the sides of and beneath the presser foot and so as to 10 be straddled by the sewing needles, said channel being adapted to permit the unobstructed passage of fasteners of the tape beneath said presser foot, and means for guiding said fastener tape to said feed-plate so 15 as to enter the fasteners thereof in said feed-plate channel for passage therethrough.

16. In combination with an attachment for guiding garment fastener-provided tape to the stitching mechanism of a sewing machine, a setting gauge comprising a base-plate, a slide movably disposed upon said base-plate, and a finger connected with said slide and extending therefrom and over a portion of said guiding attachment.

25 17. In combination with an attachment for guiding garment fastener-provided tape to the stitching mechanism of a sewing machine, a setting gauge comprising a base-plate, a slide movably disposed upon said base-plate, said slide being provided with an elongated opening, a securing plate disposed over said opening, said securing plate being provided with screw-receiving perforations, thumb-screws having their shanks extending 35 through said perforations and through the elongated opening in said slide, and screwed into said base-plate, and a finger connected with said slide and extending therefrom and over a portion of said feed-attachment.

40 18. In combination with an attachment for guiding garment fastener-provided tape to the stitching mechanism of a sewing machine, said attachment comprising a main guide-member formed with a tape-receiving 45 channel, a plurality of adjusting guides adjustably mounted upon said guide-member and bridging said channel, said guide-members being provided with hook-shaped marginal members in embracing relation with the marginal edge-portions of said main 50 guide-member, and means connected with said adjusting guides for securing said guides in fixed positions upon said main guide-member.

55 19. In combination with an attachment for guiding garment fastener-provided tape to the stitching mechanism of a sewing machine, said attachment comprising a main

guide-member formed with a tape-receiving channel, a plurality of adjusting guides adjustably mounted upon said guide-member and bridging said channel, said guide-members being provided with hook-shaped marginal members in embracing relation with the marginal edge-portions of said main 60 guide-member, and means connected with said adjusting guides for securing said guides in fixed positions upon said main guide-member.

20. In combination with an attachment for guiding garment fastener-provided tape to the stitching mechanism of a sewing machine, said attachment comprising a main 70 guide-member formed with a tape-receiving channel, a plurality of adjusting guides adjustably mounted upon said guide-member and bridging said channel, said guide-members being provided with hook-shaped marginal members in embracing relation with the marginal edge-portions of said main 75 guide-member, said adjusting guides being provided with screw-threaded perforations, and thumb-screws screwed into said perforations, for engagement with portions of said main guide-members for securing said adjusting guides in fixed positions upon said main guide-member.

21. In a sewing machine having a feed 85 plate, a presser foot adapted to contact therewith, and a channel plate adjacent said feed plate, means to permit the free unobstructed passage of a tape having separable fastening devices secured thereto, between said 90 presser foot and feed plate, said means comprising a channel in said feed plate intermediate the sides of and beneath said presser foot.

22. In a sewing machine having a feed 95 plate, a presser foot adapted to contact therewith and a channel plate adjacent said feed plate, means to permit the free unobstructed passage of a tape having separable fastening devices secured thereto between said presser 100 foot and feed plate, said means comprising a channel in said feed plate, and means to guide said tape to the feed plate comprising a channel in alignment with said first mentioned channel located below the top of said 105 channel plate.

In testimony that I claim the invention set forth above I have hereunto set my hand this 8th day of September, 1922.

GLENN BOGDONOFF.
